PENHOLDER

Filed Oct. 7, 1929

Inventor:

I. C. Bradley
By Monroe E. Miller

Attorney.

UNITED STATES PATENT OFFICE

IRWIN C. BRADLEY, OF BRATTLEBORO, VERMONT

PENHOLDER

Application filed October 7, 1929. Serial No. 398,041.

The present invention relates to penholders, and aims to provide a novel and improved penholder of simple and inexpensive manufacture from which the pen point or nib may be conveniently and quickly ejected.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

15 The invention is illustrated in the accompanying drawing, wherein—

Figure 1 is a longitudinal section of the handle or stem showing the nib holding and ejecting member and other parts in side elevation.

Fig. 2 is a longitudinal section of the penholder showing the nib being ejected.

Figs. 3 and 4 are cross-sections on the respective lines 3—3 and 4—4 of Fig. 1.

25 The penholder comprises a handle or stem 1 usually turned from wood, and having the recess 2 in its lower or outer end.

Disposed within said recess is the nib holding and ejecting member, which is composed 30 of a strip of suitable metal bent into substantial U-shape and having the opposite arms 3 and 4 at the opposite sides of the recess, and the yoke portion 5 connecting the inner ends of said arms.

35 The nib or pen point 6 is inserted between the arm 3 and the wall of the recess, and is held by friction. The arm 3 has an aperture 7 and an outstruck abutment or stop 8 at the inner edge of said aperture against which 40 the inner end of the nib abuts, thereby limiting the insertion of the nib into the holder.

The arm 4 is provided at its outer terminal with a finger piece 9 extending at an angle away from the nib and adapted for the engagement of the thumb or finger for sliding the nib holding and ejecting member outwardly, as seen in Fig. 2, for ejecting the nib from the holder.

45 A nail or pin 10 is driven into the handle 50 1 from the bottom of the recess, and extends

into said recess, and the head 11 of said nail or pin serves as a stop to limit the outward movement of the nib holding and ejecting member.

The pin 10 extends through the yoke portion 5 of said member, and the aperture 12 in said yoke portion is square or non-circular to correspond with the similar cross-section of the pin, thereby preventing the nib holding and ejecting member from rotating in the recess 2. Said member will therefore remain in the same angular position with reference to the handle.

The present construction is both inexpensive and simple in manufacture, and the pen point or nib is conveniently inserted. When the nib or pen point is to be changed it is readily ejected by pushing outwardly on the finger piece 9, thereby releasing the nib, and by returning the nib holding and ejecting member a new nib is quickly inserted.

Having thus described the invention, what is claimed as new is:

1. A penholder comprising a handle having a recess, and a nib holding and ejecting member slidable in the recess and having a yoke portion and opposite arms extending outwardly therefrom, one arm having an outstruck nib abutment, and the other arm having a finger piece at its extremity, and means 75 engaging with the handle and slidably with the yoke portion for guiding the member in its sliding movement in said recess.

2. A penholder comprising a handle having a recess, a nib holding and ejecting member slidable in said recess, and a pin entering the handle and projecting into said recess and having a stop to limit the outward movement of said member.

3. A penholder comprising a handle having a recess, a nib holding and ejecting member slidable in said recess, and a pin entering said handle and projecting into said recess and having a stop to limit the outward movement of said member, said member having a 90 non-circular aperture receiving said pin and the pin being of similar cross-section to prevent the rotation of said member in the recess.

4. A penholder comprising a handle having a recess, a nib holding and ejecting mem- 100

ber slidable in said recess having a yoke portion and opposite arms extending outwardly from said yoke portion, and a pin entering the handle and extending into the recess through said yoke portion, said pin having a head to limit the outward movement of said member.

5. A penholder comprising a handle having a recess, a nib holding and ejecting member bent from a strip of metal and having a yoke portion and arms extending outwardly therefrom and slidable along opposite sides of said recess, one arm having an outstruck nib abutment, the other arm having a finger piece at its extremity, and a pin entering said handle and projecting into said recess and having a head to limit the outward movement of said member, said yoke portion having an aperture of non-circular outline through 20 which the pin extends and the pin being of corresponding cross-section to prevent said member from turning in said recess.

In testimony whereof I hereunto affix my signature.

25

IRWIN C. BRADLEY.
